UNITED STATES PATENT OFFICE

THOMAS S. MERRYLEES, OF YEADON, PENNSYLVANIA

COOLING OF LIQUIDS

Application filed July 18, 1928. Serial No. 293,182.

This invention relates to cooling or refrigeration of liquids, particularly drinking water or beverages; its object being to render practical the use of solid carbon dioxide or the like as a refrigerant for the purpose. The solid product is manufactured from the gas which, by compression, cooling and expanding is converted into snow flakes and the snow flakes subsequently compressed into blocks of suitable size for convenience in handling and shipment commercially. Carbon dioxide as a solid has a temperature of -109° F., hence this solid contains a plus quantity of refrigeration. It sublimates when attacked by heat, i. e. the carbon dioxide returning to the original gaseous state without leaving either a liquid or a solid residue. Evaporation takes place moreover without objectionable or harmful results since the gas is absolutely odorless, tasteless and non-poisonous.

One way in which advantage may be taken of the described favorable and highly desirable characteristics of solid carbon dioxide to cool or refrigerate liquids economically with avoidance of freezing will be manifest from the detailed description which follows when taken in connection with the attached drawings.

30 Fig. I is a perspective view of a novel water cooler of the invert bottle or fountain type convenient to the practice of my invention.

Fig. II is a plan sectional view of the cooler taken about midway of its height.

35 Figs. III and IV are vertical sections respectively in planes at right angles, taken as indicated by the arrows III—III and IV—IV in Fig. II; and,

Fig. V is a fragmentary detail sectional view of the structure featuring a valve which operates to relieve excess pressure incidental to evaporation of the expanded carbon dioxide gas within the cooler.

45 As herein shown, the cooler comprises a receptacle in the form of a cylindrical well 10 preferably fashioned from porcelain or the like semi-insulatory material with a circumferential flange 11 about its top, the said flange being recessed as at 12 for lodgment of a cushioning gasket 13 to support a con-

tainer or bottle 14 for the liquid which is to be refrigerated. In the present instance, the bottle 14 is inverted with its neck fluid-sealed within the receptacle 10, thus constituting a font from which a continuous supply of the liquid is available at said receptacle. A heavy insulatory jacket 15, preferably of cork composition or the like, snugly embraces the receptacle except for a very narrow clearance interval or passage 16 immediately about the side wall of the latter. At diametrically opposite points the jacket 15 affords hollows 17, which, in practice, are just large enough to accommodate standard size blocks B of the refrigerant,—say, for example, half pound blocks measuring approximately 4 by 2 by 1 inches. As shown, the hollows 17 communicate directly with the interval or passage 16 aforesaid, and are protected by removable closures 18 having a wedge fit into the jacket 15. To insure fluid tightness, the closures 18 are edge lined with suitable sealing material as at 19, and firmly secured in position by clamp devices generally designated by the numeral 20. These clamp devices 20 may each comprise, as shown in Figs. I and II, a pair of inter-engaging draw members 21, 22 which are respectively attached, by means of interposed links 23, to the ends of a divided strap 24 extending about the jacket 15.

In order to positively maintain the blocks B of the refrigerant in surface pressure contact with those portions of the side wall of the receptacle 10 exposed within the hollows 17, I provide means which include presser members having the form of plates 25 that are subject to the urge of compression springs 26 occupying metal lined recesses 27 in the closures 18. Movement of the presser plates 25 is guided through attached pins 28 slideable in sockets 29 in the closures 18 above and below the spring recesses 27, and retained in assembly with said closures as a consequence of cooperation between stop heads 30 on the inner ends of the guide pins 28 and the contiguous ends of the metallic bushings 31 lining the sockets 29.

The receptacle 10 is drained through a pipe connection 32 extending radially through the

side wall of the jacket 15 to the exterior where a push faucet 33 is attached to its end.

For the purpose of relieving excess pressure generated incidental to evaporation of the carbon dioxide within the cooler (the liberated gas expanding to the extent of nine cubic feet to the pound at atmospheric pressure), I provide a duct 35 which leads downward to the exterior through the insulate 10 wall of the jacket 15 from a point at the top of the interval or passage 16 about the receptacle 10. At its outer end, this duct 35 is fitted with an automatic relief valve 36 in which the closure ball 37 is normally held 15 against its seat by a spring 38, as shown in Fig. V.

In operation it will be seen that the water in the receptacle 10 is cooled through direct contact of the ice blocks B with the wall of 20 the latter. As evaporation of the carbon dioxide blocks B takes place within the cooler, it diffuses in the passage 16 around the receptacle 10, and, in so doing, cools the latter in the intervals between the regions of direct contact of said blocks. By reason of 25 the smallness of the diffusing passage 16 evaporation is effectively held in check or retarded with attendant economy in the consumption of the ice blocks B. When the 30 pressure builds up to a point where the spring 38 of the relief valve 36 is overcome, the ball 37 is displaced from its seat to permit escape of the excess from time to time. Danger of 35 freezing of the liquid within the receptacle 10 is obviated as a consequence of exposure of the main supply within the bottle 14 to atmospheric influence. With a five gallon bottle 40 cooler constructed in accordance with my invention, a pound of solid carbon dioxide can be made to serve for a period of 15 hours or more with maintenance of the water in the receptacle 10 at a palatable temperature. Usually it takes about 25 pounds of ordinary 45 cracked ice to attain the same end, costing as much, if not more, than a single pound of the dry ice. The efficiency of my improved cooler is attributable to its novel construction especially in view of the smallness of the space 16 allotted interiorly for evaporation 50 of the ice blocks B, the proportionate thickness of the insulating material 15, and direct surface pressure contact of the ice blocks B with the wall of the receptacle 10 containing the liquid being refrigerated.

From the foregoing it will be further seen 55 that the cooler of my invention is simple and inexpensive to construct, easily charged with the refrigerant, and never needs any attention as regards cleaning or draining as is the case with coolers designed for use of ordinary ice, since the carbon dioxide evaporates completely without either liquid or solid residue.

Having thus described my invention, I claim:

1. In a liquid cooler adapted for use of

solidified carbon dioxide, a receptacle for the liquid, and an insulating jacket snugly embracing the receptacle except for provision of a hollow to accommodate a charge of the solid refrigerant in contact with a portion of the wall of said receptacle. 70

2. In a liquid cooler adapted for use of solidified carbon dioxide, a receptacle for the liquid, and an insulating jacket surrounding the receptacle to be refrigerated with provision of a narrow diffusing passage thereabout and a communicating hollow to accommodate a charge of the solid refrigerant in contact with the wall of said receptacle. 75

3. In a liquid cooler adapted for use of solidified carbon dioxide, a refrigerating receptacle containing the liquid, and an insulating jacket surrounding the receptacle with provision thereabout of a narrow diffusing passage and a communicating hollow to accommodate a charge of the solid refrigerant in contact with the wall of the receptacle, said passage having pressure relief by way of a duct leading through the insulation of the jacket to the exterior. 80

4. In a liquid cooler adapted for use of solidified carbon dioxide, a receptacle for the liquid, an insulating jacket surrounding the receptacle with provision thereabout of a narrow diffusing passage and a communicating hollow to accommodate a charge of the solid refrigerant, said passage having communication with the exterior by way of a duct leading downward through the insulation of the jacket, and a valve controlling relief of 95 excess pressure attendant upon evaporation of the refrigerant within the cooler. 100

5. In a liquid cooler adapted for use of solidified carbon dioxide, a refrigerating receptacle containing the liquid, and an insulating jacket snugly embracing the receptacle except for provision of a hollow just 105 large enough to accommodate a block of the solid refrigerant in surface pressure contact with a portion of the wall of said receptacle. 110

6. In a liquid cooler adapted for use of solidified carbon dioxide, a receptacle for the liquid, an insulating jacket snugly embracing the receptacle except for provision of a hollow to accommodate a charge of the solid refrigerant, and means operative to maintain 115 the refrigerant in contact with a portion of the wall of said receptacle. 120

7. In a liquid cooler adapted for use of solidified carbon dioxide, a receptacle for the liquid, an insulating jacket surrounding the receptacle with provision of a hollow just large enough to accommodate a block of the solid refrigerant, and means operative to yieldingly maintain the block of the refrigerant in surface pressure contact with said receptacle. 125

8. In a liquid cooler adapted for use of solidified carbon dioxide, a receptacle for the liquid, an insulating jacket surrounding the 130

- receptacle with provision of a hollow just large enough to accommodate a block of the solid refrigerant, a removable closure permitting access to the hollow, and means on the closure for maintaining the block of the refrigerant yieldingly in surface pressure contact with the wall of the receptacle aforesaid.
9. In a liquid cooler adapted for use of solidified carbon dioxide, a receptacle for the liquid, an insulating jacket surrounding the receptacle with provision of a hollow just large enough to accommodate a block of the solid refrigerant, a removable closure for the hollow, and a spring urged member on the closure to bear against the block of the refrigerant in maintaining it in surface pressure contact with the wall of the receptacle aforesaid.
10. In a liquid cooler adapted for use of solidified carbon dioxide, a receptacle for the liquid, an insulating jacket surrounding the receptacle with provision of a hollow just large enough to accommodate a block of the solid refrigerant, a closure for the hollow having a wedge fit with the insulating jacket, means on the closure for maintaining the block of the refrigerant yieldingly in surface pressure contact with the wall of the receptacle aforesaid, and means for securing the closure in place with assurance of an air tight seal.
11. In a liquid cooler adapted for use of solidified carbon dioxide, a receptacle for the liquid, an insulating jacket surrounding the receptacle with provision of a hollow to accommodate a charge of the solid refrigerant, a closure for the hollow having a wedge fit with the insulating jacket, and clamp strap means to secure the closure with assurance of an air tight seal.
12. In a liquid cooler adapted for use of solidified carbon dioxide, a receptacle for liquid to be cooled delivered from an exteriorly exposed inverted container constituting a continuous supply font, and an insulating jacket snugly embracing the receptacle except for provision of a hollow to accommodate a charge of the solid refrigerant in contact with a portion of the wall of the receptacle.
13. In a liquid cooler adapted for use of solidified carbon dioxide, a receptacle for liquid to be cooled delivered from an exteriorly exposed inverted container constituting a continuous supply font, and an insulating jacket surrounding the receptacle with provision thereabout of a narrow diffusing passage and a communicating hollow to accommodate a charge of the solid refrigerant in contact with the wall of the receptacle.
14. In a liquid cooler adapted for use of solidified carbon dioxide, a receptacle for liquid to be cooled delivered from an exteriorly exposed inverted container constituting a continuous supply font, and an in-
- sulating jacket surrounding the receptacle with provision thereabout of a narrow diffusing passage and communicating hollows at diametrically opposite points to accommodate charges of the solid refrigerant in contact with the wall of the receptacle, said diffusing passage having pressure relief by way of a duct leading downward through the insulation of the jacket to the exterior, closures affording access to the hollows aforesaid, and means to secure the closures with assurance of an air tight seal.
15. In a liquid cooler adapted for use of solidified carbon dioxide, a receptacle for liquid to be cooled delivered from an exteriorly exposed inverted bottle constituting a continuous supply font, an insulating jacket surrounding the receptacle with provision of hollows at diametrically opposite points to accommodate charges of the solid refrigerant in contact with the wall of the receptacle, and removable closures affording access to the hollows aforesaid.
16. In a liquid cooler adapted for use of solidified carbon dioxide, a receptacle for liquid to be cooled delivered from an exteriorly-exposed inverted bottle constituting a continuous supply font, an insulating jacket surrounding the receptacle with provision of hollows at diametrically opposite points just large enough to accommodate blocks of the solid refrigerant, closures affording access to the hollows, and means on the closures for maintaining the blocks of the refrigerant yieldingly in surface pressure contact with the wall of the receptacle aforesaid.
17. The method of refrigerating liquids without freezing them by use of solidified carbon dioxide maintained by non-gravitational pressure in outside surface contact with the wall of a semi-insulatory material receptacle containing the liquid being refrigerated.
18. The method of refrigerating liquids without freezing them by use of a block of solidified carbon dioxide maintained by mechanical pressure in outside surface contact with the wall of a porcelain receptacle containing the liquid being refrigerated.
19. The method of refrigerating liquids without freezing them by use of a block of solidified carbon dioxide maintained under mechanically-enforced pressure, while protected against external atmospheric influence, in outside surface contact with the wall of a porcelain receptacle containing the liquid being refrigerated.
20. The method of refrigerating liquids without freezing them by use of solidified carbon dioxide blocks maintained by non-gravitational influence in outside surface pressure contact with the wall of a porcelain receptacle containing liquid delivered from a continuous source of supply exposed to external atmospheric influence.

21. In a liquid cooler adapted for use of solidified carbon dioxide, a ceramic refrigerating receptacle containing the liquid, and an insulating jacket surrounding the receptacle with provision thereabout of a narrow diffusing passage and a communicating hollow to accommodate a charge of the solid refrigerant in outside surface pressure-contact with the wall of the receptacle, said passage having pressure relief by way of a duct leading through the insulation of the jacket to the exterior.

22. In a liquid cooler adapted for use of solidified carbon dioxide, a porcelain receptacle for the liquid, an insulating jacket surrounding the receptacle with provision thereabout of a narrow diffusing passage and a communicating hollow to accommodate a charge of the solid refrigerant, in outside surface pressure-contact with the wall of the receptacle, said passage having communication with the exterior by way of a duct leading through the insulation of the jacket, and a valve at the outer end of said duct controlling relief of excess pressure attendant upon evaporation of the refrigerant within the cooler.

23. The method of cooling liquids without freezing them by use of a solidified binary-compound capable of sublimation without residue maintained by non-gravitational pressure-influence in outside surface-contact with the wall of a semi-insulatory container containing the liquid being cooled.

24. The method of cooling liquids without freezing them by use of a solidified frigorific binary-compound capable of sublimation without residue and maintained under non-gravitational pressure-influence in outside surface-contact with the wall of a porcelain receptacle containing the liquid being refrigerated.

25. The method of refrigerating liquids without freezing them by the use of solidified carbon dioxide maintained under non-gravitational pressure-influence in outside surface-contact with the wall of a ceramic receptacle containing the liquid being refrigerated.

26. A liquid cooler for the purpose set forth comprising a ceramic receptacle for the liquid being cooled, an exteriorly exposed inverted container seating on said receptacle and constituting a continuous supply font, an insulating medium base in which the ceramic receptacle substantially seats, said base having opposed cavities accommodating solidified blocks of carbon dioxide, removable closures for said cavities, and means associated with said closures yieldingly sustaining the aforesaid blocks in surface pressure contact with the wall of the ceramic receptacle.

In witness whereof, I have hereunto signed my name at Philadelphia, Pennsylvania, this 13th day of July, 1928.
